UNITED STATES PATENT OFFICE.

THOMAS WEST, OF LOUISVILLE, KENTUCKY.

STEAM COOKING OR WARMING ATTACHMENT FOR STOVES.

1,319,544.

Specification of Letters Patent.

Patented Oct. 21, 1919.

Application filed July 12, 1918. Serial No. 244,613.

To all whom it may concern:

Be it known that I, THOMAS WEST, a citizen of the United States, residing at Louisville, in the county of Jefferson and State 5 of Kentucky, have invented certain new and useful Improvements in Steam Cooking or Warming Attachments for Stoves, of which the following is a specification.

This invention relates to improvements in 10 attachments for liquid and gaseous fuel burning stoves and it is the principal object of the invention to provide a steaming attachment therefor whereby to permit the cooking of matter by steam when necessary 15 or to allow the warming of the same subsequent to the cooking thereof, thus providing an exceedingly useful and desirable device for use in homes or cafés as well as a device which can be attached to practically 20 all forms of liquid and gaseous fuel burning stoves with but slight alteration thereto.

Other objects will be in part obvious and in part pointed out hereinafter.

The improvements in the details and arrangement of parts will be apparent from 25 an inspection of the accompanying drawings, when considered in connection with the specific description hereinafter contained and wherein the preferred embodiment of 30 the invention is disclosed for the purpose of imparting a full understanding thereof.

In the drawings:

Figure 1 is a fragment of a top of a liquid or gaseous fuel burning stove showing 35 the improved attachment in top plan supported in one side thereof, and

Fig. 2 is a fragmentary side elevation of the stove showing the attachment connected thereto and in section.

Having more particular reference to the drawings, in connection with which like reference characters will designate corresponding parts throughout the several views, 1 represents a portion of a liquid or gaseous 45 fuel burning stove provided with the usual fuel supply pipe 2, which as will be understood has branch pipes tapped thereinto and controlled by valves generally indicated by the numeral 3 whereby passage of gas or 50 other fuel from the supply pipe 2 to the various burners of the stove can be controlled. In this connection, it is to be noted that the fuel supply pipe 2 is extended as at 2', the purpose of which will be herein- 55 after described.

Openings are formed in one end of the

top of the stove 1 and have bracket arms 4 connected at certain of their ends thereto by bolts 5 or similar fastening devices. In this connection, it is to be noted that a pair of 60 bracket arms 4 are provided, but, if desired, the number may be varied, such as conditions or preference may dictate.

Seated in the bracket arms 4 is a receptacle 6, the sides of which are tapered and 65 conform to the sides of the several bracket arms 4; said receptacle having a drain opening formed in the bottom thereof receiving a suitable form of drain cock 7 therein for 70 an obvious purpose.

Arranged over the open upper end of the receptacle 6 is a shelf 8 having a series of receptacle receiving openings 9 formed therein for receiving pots and pans or similar cooking utensils such as indicated by 75 the numeral 10. In this connection, it is of course to be understood that lids 11 can be arranged over the various openings 9 and the open upper ends of the receptacles 10 arranged therein, thus, permitting the contents 80 thereof to receive full benefit from the steam given off by the heated liquid arranged in the receptacle 6.

Engaged with the outer end of the extension 2' of the supply pipe 2, which as will 85 be noted, is screw threaded in an elbow 12 having a branch pipe 13 connected thereto, which branch pipe is in turn connected to one end of a perforate burner pipe 14 extending longitudinally of the receptacle 6 in 90 spaced relation to the bottom thereof. A suitable form of valve 15 is interposed in the burner pipe 14 and obviously serves as means for permitting the passage of the fuel through the openings therein to be controlled at will by a user. To permit the proper mixture of air with the fuel flowing into the burner pipe 14, I form an opening 95 16 in one end of said pipe, which opening can be varied by an ordinary sleeve valve 100 arranged about the same, such construction being common in the art.

From the foregoing, it will be readily understood by persons skilled in the art that I have provided an exceedingly effectual 105 and simple form of steam cooking or heating attachment for liquid or gaseous fuel burning stoves, and furthermore, a device which will be extremely desirable for use in homes, cafés, etc., wherein some means 110 to maintain the temperature of foodstuff at a predetermined degree subsequent to the

cooking thereof is desired. It is to be also noted, that the device can be attached to practically any form of liquid or gaseous fuel stove now marketed with but slight alteration thereto.

Manifestly, the construction shown is capable of considerable modification and such modification as is within the scope of my claim, I consider within the spirit of my invention.

I claim:

The combination with a gaseous fuel burning stove having a fuel supply pipe, of brackets fixed to the stove, a receptacle

mounted within said brackets and open at 15 its top, a cover plate fitted upon the open top of the receptacle and forming a shelf having a plurality of openings therein to accommodate cooking utensils for the suspension of the same within the receptacle, 20 and a burner connected with the fuel supply pipe of the stove and extending exteriorally of and beneath said receptacle longitudinally thereof.

In testimony whereof, I affix my signature 25 hereto.

THOMAS WEST.
